SHIPPING BOX

John E. Borah and Judith M. Borah,
Osceola, Ind.

Application July 11, 1941; Serial No. 402,004

1 Claim. (Cl. 229—31)

This invention relates to shipping boxes, and more particularly to shipping boxes made from paper board, such as kraft lined corrugated board, jute corrugated board, or the like.

The primary object of the invention is to provide a box which is strong in construction, inexpensive, easy to erect, and which is formed from a single blank.

A further object is to provide a shipping box which is formed from a single blank and which has a strong reinforced construction at all vertical edges or corners.

A further object is to provide a box, formed from a single blank, with multiple thickness portions reinforcing the end portions of the front and back walls.

A further object is to provide a box, formed from a single blank, and having a folding cover, with means for reinforcing the fold upon which the cover hinges.

A further object is to provide a box, formed from a single blank and having a folding cover, with means at the upper portions of the box ends for supporting the ends of the cover when closed to prevent collapse of the cover into the box under pressure.

A further object is to provide a box, formed from a single blank and having a folding cover and a locking tab at the free end of the cover, with an integral folded portion at the upper end of the box for supporting the free end of the cover and retaining the locking tab.

A further object is to provide a shipping box having a folded cover, which is constructed and arranged to accommodate locking or sealing of the cover by the use of staples.

A further object is to provide a shipping box having a folded cover, a locking tongue at the outer end of the cover adapted to extend adjacent a vertical box wall, and horizontal flanges at the upper edges of the box ends to overlie the marginal cover portions, wherein staples secure the cover tab to the adjacent box wall and secure the margins of the cover to the flanges underlying the same.

A further object is to provide a box having a cover folded from the upper edge of one wall thereof and flanges folded from the box and cover, and extending adjacent another box part, wherein the box and cover are slotted adjacent said flanges to receive the anvil of a stapling machine adapted to staple said flanges to the adjacent box parts for the purpose of sealing the box.

A further object is to provide a box with a folding cover having a downturned flap portion carrying an upturned flap portion at its free end, whereby said flap portions form a pocket closed at its lower end and adapted to receive the anvil of a stapling machine for the purpose of stapling the outermost flap to an adjacent box wall while the innermost flap prevents engagement of said anvil with the contents of the box.

10 A further object is to provide a box with a folding cover wherein portions of the box and of the cover are arranged in face juxtaposition to be stapled together, and wherein a return bent flange is provided on the inner end of the innermost stapled part to protect and separate the box contents from the stapled part.

Other objects will be apparent from the description, drawings, and appended claims.

In the drawings:

20 Fig. 1 is a plan view of the blank utilized in making the box.

Fig. 2 is a perspective view of the box with the cover open.

Fig. 3 is a perspective view of the box with the cover closed.

Fig. 4 is a transverse vertical sectional view of the box taken on line 4—4 of Fig. 3.

Fig. 5 is a longitudinal vertical sectional view of the box taken on line 5—5 of Fig. 3.

30 Fig. 6 is a fragmentary detail sectional view of the box taken on line 6—6 of Fig. 4.

Fig. 7 is a fragmentary detail sectional view of the box taken on line 7—7 of Fig. 5.

35 Fig. 8 is a fragmentary detail sectional view corresponding to Fig. 7 but illustrating a modified embodiment of the invention.

Fig. 9 is a fragmentary detail sectional view of the box similar to Fig. 7 but illustrating another modified embodiment of the invention.

40 Referring to the drawings, which illustrate the preferred embodiment of the invention, the numeral 10 designates a blank formed of paper board, such as kraft lined corrugated board, jute corrugated board, or the like. This blank is cut to the outline illustrated in Fig. 1 to provide a substantially rectangular central transverse portion thereof defined by parallel fold lines 11. This central portion of the box provides, in alignment, a front panel 12, a bottom panel 13, a back panel 14, a cover panel 15, and a flange 16 at the outer end of cover panel 15. Flange 16 is either of a length shorter than the length of the cover panel, as shown in Fig. 2, or has its ends cut at substantially 45° to fold line 20 as shown in Figs. 1 and

5. A longitudinal fold line 17 separates the front panel 12 from the bottom panel 13, longitudinal fold line 18 separates the bottom panel 13 from the back panel 14, a longitudinal fold line 19 separates the back panel 14 from the cover panel 15, and a longitudinal fold line 20 separates the panel 15 and the cover flange 16.

Lateral portions extend at opposite sides of the central portion of the blank above described, between the fold lines 11 and transverse fold lines 21 spaced inwardly from each end of the blank. End panels 22 are formed in the blank at opposite ends of and longitudinally aligned with the bottom panel 13, and are defined by the fold lines 11, 21, 17 and 18. Square reinforcing panels are formed at opposite sides of each of the end panels 22 and are provided with diagonal central fold lines 23 which extend therethrough from the junctions of the fold lines 17 or 18 with the fold lines 11. These fold lines 23 divide the square reinforcing panels into triangular panels 24. Rectangular panels 25 project from the uppermost reinforcing panels 24 and are defined at their lower edges by the longitudinal fold lines 19. The inner edges of the flanges 25 are defined by slots 26 extending from the upper edges thereof to the fold line 19.

Each end of the blank is provided with a rectangular flange portion 27 opposite and aligned with the end panels 22 and defined by the fold lines 17, 18 and 21. From the upper and lower ends of flange portions 27 extend square reinforcing panels 28 which are provided with diagonal fold lines 29 which extend from the outer corners thereof to the junction of the fold lines 17 or 18 with the fold line 21.

When the box is to be erected, the blank is folded along lines 11, 17, and 18, and the rectangular reinforcing portions are folded inwardly along the diagonal fold lines 23 to bring the two triangular panels 24 into engagement with each other and with the adjacent front and back panels 12 and 14. Suitable securing means, such as staples 30, are then passed through the two triangular panels 24 and the adjacent one of the front and back walls, for the purpose of securing the box in erected position with the walls 12, 14, and 22 all in vertical position. The flanges 25 will then be positioned in face engagement with the cover 15, and they are stapled to the cover 15 by means of the staples 31. The staples 30 and 31 serve as the sole means for securing the box in erected position, although it will be understood that, in the event the flanges 25 are eliminated, only the staples 30 would be employed to hold the box erect.

When the box has been erected as aforesaid, the end flanges 27 and the square reinforcing panels 28 will then extend in vertical position, as illustrated at the left in Fig. 2, to fully expose the interior space of the box. This permits the box to be packed quickly and efficiently, without interference from any part projecting over the space within the box walls. Thereupon, the reinforcing panels 28 may be folded inwardly along diagonal fold line 29 and longitudinal fold lines 17 and 18 to position the end flanges 27 horizontally as illustrated at the right in Fig. 2. When the end panels 27 are in horizontal position, the triangular portions of the reinforcing panels 28 on opposite sides of the front line 29 will extend in vertical position bearing against the front and back walls of the box, and will serve as means at the ends of the flanges 27 for effectively and positively supporting said flanges 27 in horizontal

position. Thereupon, the cover of the box is folded to horizontal position about the fold line 19 to assume a position with its transverse marginal portions bearing upon and supported by the end flanges 27. The cover tab 16 is folded downwardly and is adapted to extend within the box where its opposite ends are received in the pockets defined by the inner and outer triangular portions of the folded flange reinforcing panel 28.

This construction serves to support the free end of the cover in a manner to prevent its depression into the box, and also serves to insure retention of the cover tab 16 in its closed position. It will be understood in this connection that many boxes provided with folding covers are subjected, when loaded, to stresses which tend to urge the box cover upwardly away from the top of the box, and which make it difficult to seal the box because of the necessity on the part of the operator to manually hold the cover closed while performing the sealing operation. In the instant box, once the operator has inserted the ends of the cover flange 16 into the pockets provided by the folded reinforcing panel portions 28, said folded portions grip said flange in a manner to insure retention thereof in said pockets, and thereby to prevent the box lid from springing upwardly from fully seated or closed relation.

Attention is specifically called to the following important features of this box. First, the reinforcement of the long dimension vertical walls of the box, namely, the front wall 12 and the back wall 14, by virtue of the securing of triangular reinforcing panels 24 thereto. This not only strengthens the elongated vertical walls of the box, but also reinforces each of the four vertical box corners. Second, the securing of the tabs 25 to the box cover serves to reinforce the fold 19 about which the cover 15 hinges. In connection with this feature it will be apparent that one of the critical points of any paper board box having a folded cover is the fold line between the back wall and the cover. When the boxes are loaded with material which must be compressed to permit full closing of the cover, such as material in the nature of clothing or the like, a substantial strain is exerted upon the fold line 19 between the vertical box wall and the cover. In the instant construction the securing of the portions 25 to the cover provides a double thickness box portion along the major portion of the fold line 19 and adjacent the two ends thereof, so that all stress which is exerted upon the fold lines is taken up by two thicknesses of material and the danger of breakage or tearing of the box material at this fold line is substantially avoided. Third, the end flanges 27 of the box are positively supported in horizontal position by means of the integral folded reinforcing panels 28, so that said end flanges form a positive weight sustaining reinforcement underlying the opposite ends of the cover and serve to insure against collapse of the cover into the box when heavy stresses are applied to the cover. Fourth, the seating of the cover flap 16 within the box and within the pocket formed by the folded panel 28 serves to support the free end of the box against collapse and to lock the cover against springing thereof to open position under torque or stress applied to the box.

For the purpose of sealing the box, the cover 15 is preferably provided with one or more short narrow slots 35 whose outer edges substantially coincide with the fold line 20. These slots are spaced from the opposite ends of the cover 15,

and, if a plurality thereof is provided, are also spaced substantially from each other. Slots 35 are adapted for the reception of an elongated narrow anvil-carrying arm 36 of any conventional stapling machine 37, as illustrated in dotted lines in Fig. 8, which may be employed for the purpose of applying a staple 38 to the box to pass through and secure together the cover flange 16 and the front wall 12 of the box. The slots 35 may be of small size so as not to interfere with the strength of the box nor to permit tampering with or pilfering of the box contents. Thus, it is possible to restrict the size of these slots to a width of about $\frac{1}{8}$ of an inch and to a length of about $\frac{3}{4}$ of an inch. One or more slots 39 may be formed in the upper portion of each end wall 22 with its upper edge substantially coinciding with the fold line 21 for the purpose of receiving the anvil arm of a stapling machine for applying a staple 40 to secure each end flange 27 to one of the end margins of the cover 15. The advantages of staples 38 and 40 as box seals are: simplicity; low cost; facility of application by hand; avoidance of necessity for handling or manipulation of the box while loaded to effect sealing thereof; avoidance of cutting of the box incident to the sealing, as may occur where tensioned binding members encircling the box are utilized to seal the same; and elimination of projections, such as the knots of box-encircling members.

A further improvement of the invention is illustrated in Figs. 8 and 9. This improvement involves the provision of a tab or flange 41 folded from the bottom or free edge of cover flange 16 and extending in an upward direction. In the Fig. 8 embodiment, the upwardly extending tab 41 is positioned inwardly with respect to the cover tab 16; while the Fig. 9 embodiment entails the positioning of tab 41 outwardly with respect to the cover tab 16. In each instance, the two tabs 16 and 41 serve to provide a pocket open at its upper end and closed at its lower end, into which the anvil arm 36 of the stapling machine 37 may be inserted to apply the staples. In the Fig. 8 embodiment, the provision of slots 35 is necessary to permit insertion of the anvil arm 36 of the stapling machine into the pocket between tabs 16 and 41 for the purpose of securing the tab 16 to the box wall 12 by staples 38. In the Fig. 9 embodiment, the use of slots is avoided by virtue of the fact that the tab 41 is positioned outwardly of the tab 16 so that the pocket between said tabs is open to permit the insertion of the anvil arm 36 therein. In order that the type of seal shown in Fig. 9 be made fully effective, the staple 38 must be positioned close to the lower end of tab 41 and to the fold between tabs 41 and 16, so as to reduce to a minimum the possibility of any play occurring by reason of the double fold between the tab 41 and the box cover 15. Most stapling machines are constructed with the stapling anvil positioned at the extreme outer end of arm 36, so that stapling of the parts close to the fold between tabs 16 and 41 is not difficult to accomplish.

While the box sealing means has been illustrated herein as applied to the box formed from a single blank as above described, it will be obvious that such sealing means may be used with equal facility upon boxes formed of two, three or more

blanks or parts by simply providing the same with the flanges on the cover and the end walls necessary for the stapling operation, and with the access slots 35 and 39 or tabs 41. Likewise it is obvious that tabs similar to tabs 41 may be formed on the ends of the horizontal flanges 27 on the end walls 22, so that the advantages thereof can be incorporated at all points of the box which are to be stapled.

- 10 The primary purpose of tabs 41 is to confine the anvil arm 36 of the stapling machine within a restricted space in the box during its insertion and use for stapling the box parts; and to provide a separator panel between arm 36 and the contents of the box which eliminates all danger of damaging the box contents by contact with said anvil arm or by impaling of said contents by the staples. This is particularly important where the box contents are formed of fabric or other 15 non-metallic material which might easily be impaled or pierced by a staple, even when the staple is applied by a hand operated stapling machine.

Attention is also directed to two additional features of the box which greatly facilitate erection and increase its strength. The first of these is the beveled ends of cover tab 16 as shown in Figs. 1 and 5. Note particularly in Fig. 5, how the beveled form is complementary to the fold lines 29 between the triangular reinforcing portions 28, so that the cover tab fits snugly between said portions 28 and the cover is prevented from lateral dislocation relative to the box by engagement with the folds 29. This materially increases the strength of the box. The other feature is that, by locating the diagonal fold line 23 of reinforcing panel 24, and diagonal fold line 29 of reinforcing panel 28, slightly offset from true medial position so as to make the triangular portion 35 thereof adapted to be positioned outermost, slightly smaller than the other triangular portion, the folding of panels 24 and 28 along their respective fold lines 23 and 29 will automatically cause said triangular folded portions to lie flat against the adjacent front and back walls. The advantage obtained by this arrangement lies in the fact that it is not necessary to manually hold the reinforcing portions 24 during the stapling operation, and that the triangular portions 28 will extend vertically to assure solid reinforcement of end flanges 27 and to assure vertical positioning of the pocket between the front portions 28 for quick insertion of cover tab 16 therein.

I claim:

- 55 A box comprising a body part including bottom and side panels, a foldable part including a cover panel folded from the upper edge of one of said side panels, a flap folded perpendicularly inwardly from an edge of a panel of one box part and folded centrally inwardly upon itself to define inner and outer flap portions, the panel from which said flap is bent having a narrow opening between the planes of the inner faces of the two flap parts to receive and guide the anvil 60 arm of a stapling machine between said flap parts, and a staple securing the outer flap part to the adjacent panel of the other box part, said inner flap part shielding the interior of the box from dirt entering said slot.
